UNITED STATES PATENT OFFICE

JOHN BRISTOW TUCKER, OF TYSELEY, BIRMINGHAM, ENGLAND

ELECTRICAL PLUG AND SOCKET CONNECTION

Application filed August 19, 1929, Serial No. 386,792, and in Great Britain January 16, 1929.

The present invention has relation to plug-and-socket connections, more particularly though not essentially those associated with a switch mechanism in such a manner that the 5 plug pin cannot be withdrawn until such time as the switch has been opened, the present invention having for its object to provide for a particularly efficient mechanism of the aforesaid character incorporating certain facilities hereinafter referred to.

According to the present invention I provide an electrical plug-and-socket mechanism embodying in combination a plug pin member, a socket therefor, a switch mechanism associated or adapted to be associated therewith, and means connecting the switch mechanism with the socket for enabling the pin to be frictionally clutched by its socket (as differentiated from being positively interlocked or interengaged) when the switch is in the closed position and released when the switch is in the open position.

The present invention enables the standard solid or split plug pin to be employed, said 25 plug pin being efficiently clutched or gripped by the actuation of the switch mechanism, as differentiated from being positively locked by notching, grooving, slotting or other similar device, such means calling for specially prepared plug pin members and locking devices; the clutching effected by this invention is so efficacious that by the ordinary manipulation of the mechanism the plug pin cannot be withdrawn with the switch mechanism closed.

35 The clutching means may comprise a loop of spring or resilient strip metal constituting the socket and adapted to be contracted when the switch is closed by the actuation of said switch, or, alternatively, the socket may comprise a coil of spring or resilient metal wound 40 after the manner of a clock spring and adapted to be contracted as before.

The socket hereinbefore referred to may be an electrically live one or may be a socket 45 utilized in connection with an earthing circuit, or may even be completely independent of any electrical influence, and be adapted to co-operate with a plain pin on the plug solely for the purpose of locking the plug in position when the switch is closed.

In order that this invention may be clearly understood and readily carried into practice, reference may be had to the appended explanatory sheet of drawing, upon which:—

Figure 1 is a plan view illustrating switch 55 mechanism incorporating a plug-and-socket connection constructed according to the present invention.

Figure 2 is an elevational view of a strip utilized in the construction of the socket.

Figure 3 is a perspective view of the socket alone constructed from such strip.

Figures 4 and 5 are plan views of modifications hereinafter referred to.

In one embodiment of the present invention an elongated strip *a* of spring or resilient metal (see particularly Figure 2) is slotted centrally as at *a*¹ and the other half is in the form of a longitudinal central tongue *a*² which is passed through the slot as shown 70 more particularly in Figure 3. The extremity *a*³ is anchored to a stationary pillar or post *b* and the other extremity *a*² to a lever *b*¹ taking a fulcrum upon the curled socket part *a*⁴, see particularly Figure 1, and adapted to be operated by the switch mechanism to contract the socket when the switch is closed. The switch mechanism may comprise a dolly *c* pivotally mounted upon a stationary bridge *c*¹ and adapted to actuate a 80 swinging contact arm engaged with fixed contacts in well known manner. The dolly *c* is provided with a lateral extension *c*² offset from its normal pivot adapted to co-operate with a forked extension *d*¹ of an arm *d* pivoted at the point *d*² in such a manner that when the dolly *c* is manipulated the arm *d* is rocked on its pivot *d*². The arm *d* is connected to the lever *b*¹ by an insulating link *e* preferably through a lost motion connection *e*¹ and spring *e*² bearing against insulating washers *e*³, the operation being such

90 that when the contacts are made and the circuit closed the socket *a*⁴ is caused to clutch the plug pin *f* shown at the left hand part of the Figure 1, the other plug pin *f*¹ of which is adapted to engage a normally split or other tubular socket *g*. Mechanism may be incorporated whereby the switch is locked 95 in the "off" position when the plug pins are 100

withdrawn. Such mechanism may comprise a suitable button at the lower extremity of a socket (or buttons associated with each socket) which is or are displaced when the plug pins are driven home to release the switch mechanism and allow it to be closed to clutch the plug pin.

In a modification of the present invention, (see particularly Figure 4), a coil of spring or resilient strip metal h , after the manner of a clock spring, may have its inner extremity h^1 suitably secured and its outer extremity connected to a lever h^2 taking a fulcrum on the socket h , which lever is connected to the switch mechanism for the purpose aforesaid.

In a still further embodiment (Figure 5) two extremities of a spring or resilient strip i may be connected to adjacent points on a pivotal lever i^1 in such a manner that the loop is contracted by the swinging movement of the said lever i^1 , which movement is effected by the closing operation of the switch.

It is to be appreciated that the present invention provides for a standard solid or split plug pin being employed, the said plug pin being efficiently clutched or gripped by the actuation of the switch mechanism as differentiated from being positively locked by notching, grooving, slotting or other similar treatment, such means calling for specially prepared plug pin members and locking devices. The clutching effected by this invention is so efficacious that by the ordinary manipulation of the mechanism the plug pin cannot be withdrawn with the switch mechanism closed. Further, as previously stated, provision may be made whereby the clutching socket cannot be closed until such time as the plug pin has been engaged therewith. The clutching socket may be a normal socket adapted to be placed under electrical influence when the switch is closed, or may be an independent socket utilized in connection with an "earthing" circuit, or may even be completely independent of any electrical influence and be adapted to co-operate with a plain pin on the plug purely for the purpose of locking the plug in position when the switch is closed.

In each of the modifications aforeinstanced suitable insulation is incorporated in operating mechanism connecting the switch dolly to the clutching socket.

What I claim as my invention and desire to secure by Letters Patent is:

1. In combination, an electric switch, a contractile socket for the reception of a plug pin, and means whereby closing of the switch contracts said socket.

2. In combination, an electric switch, an inherently resilient contractile socket for the reception of a plug pin, said socket being maintained normally in an expanded status

by its inherent resiliency, and a connection between said switch and said socket whereby closing of the former contracts the latter.

3. In combination, an electric switch, a socket for the reception of a plug pin, and means whereby closing of the switch causes said socket to frictionally clamp a plug pin disposed therein.

4. In combination, an electric switch, a contractile band socket for the reception of a plug pin, and means whereby closing of the switch contracts said band socket.

5. In combination, an electric switch, a contractile socket for the reception of a plug pin, and a link and lever connection between said switch and said socket whereby closing of the former contracts the latter.

6. In combination, an electric switch, a contractile socket for the reception of a plug pin, means maintaining said socket normally in an expanded condition, and a connection between said switch and said socket whereby closing of the former contracts the latter.

7. In combination, an electric switch, a strip of inherently resilient sheet metal coiled upon itself to provide a contractile socket for the reception of a plug pin, and a connection between said switch and said socket whereby closing of the former contracts the latter.

8. In combination, an electric switch, a strip of sheet metal bent upon itself to provide a contractile socket for the reception of a plug pin, a lever connected with said strip at one point and fulcrumed against said socket at another point for contracting said socket, and a connection between said switch and said lever whereby closing of the former actuates the latter to contract said socket.

9. In combination, an electric switch, a contractile socket for the reception of a plug pin, a lever connected with said socket for contracting the same, and a connection between said switch and said lever whereby closing of the former actuates the latter to contract said socket.

10. In combination, a socket for the reception of a plug pin, an electric switch separate from said socket, and means whereby closing of the switch is effective to clamp a plug pin within said socket.

11. In combination, a socket for the reception of a plug pin, an electric switch separate from said socket, and means whereby closing of the switch is effective to frictionally secure a plug pin within said socket.

12. In witness whereof I have hereunto set my hand.

JOHN BRISTOW TUCKER.
